April 22, 1947.

H. WAHLBERG

2,419,513

COMBINATION GARMENT

Filed June 27, 1944

3 Sheets-Sheet 1

Inventor

HORTENSE WAHLBERG,

By Clarence A. O'Brien,
and Harvey B. Jacobson.
Attorneys

April 22, 1947.

H. WAHLBERG

2,419,513

COMBINATION GARMENT

Filed June 27, 1944

3 Sheets-Sheet 2

Fig. 3.

Fig. 4.

By

HORTENSE WAHLBERG,
Clarence O'Brien
and Harvey B. Jacobson
Attorneys

April 22, 1947.

H. WAHLBERG

2,419,513

COMBINATION GARMENT

Filed June 27, 1944

3 Sheets-Sheet 3

HORTENSE WAHLBERG,

By Charles A. O'Brien
and Harvey B. Jacobson
Attorneys

UNITED STATES PATENT OFFICE

2,419,513

COMBINATION GARMENT

Hortense Wahlberg, Miami, Fla.

Application June 27, 1944, Serial No. 542,358

3 Claims. (Cl. 2—71)

1

My invention relates to improvements in garments, the principal object in view being to provide a unitary combination garment designed for folding and draping on the person in a single piece to form a dress and shorts, and which requires a minimum of material, is secured in place without metal fasteners, and may be inexpensively produced and easily and quickly put on or taken off.

Other and subordinate objects are also comprehended by my invention, all of which, together with the precise nature of my improvements, will be readily understood when the succeeding description and claims are read with reference to the drawings accompanying and forming a part of this specification.

In said drawings—

Figure 1 is a view in front elevation of my improved combination garment as it is designed to be worn.

Figure 2 is a view in rear elevation of the garment before it is put on and in unfolded condition.

Figure 3 is a fragmentary view in front elevation illustrating the manner in which the garment is folded in putting on the same.

Figure 4 is a fragmentary view in rear elevation of the skirt forming section, and

Figure 5 is a view of the garment in spread out flat condition.

Referring to the drawings, by numerals, in the preferred illustrated embodiment thereof, my invention comprises a unitary, foldable sectional robe 1 of substantially inverted T-shape when unfolded and spread out flat which may be formed of any suitable cloth, and is patterned to provide an elongated, shield-like, waist-forming end section 2. The end section 2 is provided, in the longitudinal center thereof, with a neck opening 3 and terminates on one side of the opening 3. Said end section 2 is designed to be folded over the shoulders of the wearer upon opposite sides of the neck opening 3 to provide the waist back 4 and a waist front 5, longer than the back 4, for a purpose presently seen. The waist front 5 merges into a crotch section 6 relatively narrower than said front 5 and which, in turn, merges into a relatively wider seat-forming section 7 for the shorts which flares from the section 6. The seat-forming section 7 comprises a central upper edge extension of a relatively wider skirt forming section 8.

The described robe is suitably hemmed along its edges as represented at 9, and around the neck opening 3, as at 10.

2

The end section 2, above the crotch section 6, is provided with scalloped side edges to form a pair of opposed side edges, triangular tabs 11 in the transverse center of the waist back 4, and a pair of similar tabs 12 in the waist front 5.

A pair of tape ties 13 are suitably secured at one end to the tabs 11, and a similar pair of tape ties 14 to the tabs 12. A pair of underarm loops 14' are suitably attached to opposite side edges of the waist back 4 between the tabs 11 and the neck opening 3. A pair of ribbon-like ties 15 are attached to the waist front 5 at the side edge thereof between the neck opening 3 and the tabs 12. The waist back 4 is suitably divided, as at 16, from the neck opening to form a placket opening and provided with a button 17 and a loop 18 for closing said opening.

A pair of back ribbon-like ties 19 are provided on the skirt-forming section 8 to extend oppositely from the longitudinal center line of the robe 1 and along what constitutes the top, or waist line, of said section 8, said ties having inner end portions suitably secured, as by stitches 19, to the section.

The seat-forming section 7 and skirt-forming section 8 may be suitably gathered, as at 20, upon opposite sides of the longitudinal center of the robe 1 to shape the same. The waist back 4 may be gathered, as represented at 21, for the same purpose.

The described robe 1 is preferably formed of four pieces of cloth joined together in the longitudinal center of the robe by a seam 22 and in the transverse center of the crotch-forming section 6 by a seam 23. The skirt-forming section 8 is reinforced on the inner side thereof along said seam 22 by the hem 24. From the skirt-forming section 8, the robe 1 is reinforced along said seam 22 to the neck opening 3 by the hem 25, said hem being on the opposite side of the robe which, as will presently appear, forms the inner side of the crotch-forming section 6 and the waist front 5.

Referring now to the use of the described robe 1 in forming the garment, and to Figures 1 and 3, the waist-forming end section 2 is put on over the head of the wearer by means of the neck opening 3, with the waist back 4 and the waist front 5 draped down the back and the front of the wearer. This positions the loops 14' under the arms of the wearer. The described placket-forming opening is closed by means of the button 17 and loop 18. The ties 14 and tabs 12 are pulled rearwardly and said ties 14 tied behind the waist 55 back. The ties 13 and tabs 11 are then pulled forwardly and said ties 13 tied in front of the waist front as shown in Figure 3. One tie 15 of each pair is then passed through the loop 14' on the same side of the said section 2 to fasten the waist back 4 and waist front 5 together under the arms, and the ties 15 of the pairs are passed across the waist front 5 under and over the same with one tie of each pair extending out of the neck opening 3 and tied to the other tie of the pair as shown in Figures 1 and 3. The crotch-forming section 6 is then passed rearwardly between the legs of the wearer as shown generally in Figure 3, in which operation, as will be clear, the waist front 5 forms the front leg portions 28 of a pair of shorts. The seat-forming section 7 is then folded up behind the posterior of the wearer, as also indicated in Figure 3, the skirt-forming section 8 folded at its juncture line with said section 7 to hang downwardly, as also shown in Figure 3, and said section 8 wrapped forwardly around the waist line, hips, and legs of the wearer, as represented in Figure 1. To fasten the skirt-forming section in position, the ties 19 are brought forwardly around the sides of the waist of the wearer and tied with the upper corners of the skirt forming section 8, as shown in Figure 1, at the sides of the wearer, with the sides of said section 8 overlapping in front of the wearer and the tie 19 on each side tied with the upper corner of said section 8 which has been brought forwardly from the other side of the wearer.

The foregoing will, it is believed, suffice to impart a clear understanding of my invention without further explanation.

Manifestly, the invention as described, is susceptible of modification without departing from the inventive concept, and right is herein reserved to such modifications as fall within the scope of the appended claims.

What I claim is:

1. A garment comprising a unitary substantially T-shaped robe with the leg of the T constituting a body portion and the bar of the T constituting a skirt portion, a neck opening intermediate the ends of said leg, said leg being foldable medially of said neck opening and transversely of itself to provide upper waist front and back members open at the sides, a portion of said leg between said neck opening and the bar adapted to be positioned between the legs of the wearer and covering the lower front and back portions of the body, and open at the sides, the bar being reversely foldable upon itself, the free ends of said bar being extensible about the hips of the wearer for overlapping engagement, means for detachably securing the open sides of said waist members and additional means to detachably secure said free ends of said skirt portion.

2. A garment comprising a unitary substantially T-shaped robe with the leg of the T constituting a body portion and the bar of the T constituting a skirt portion, a neck opening intermediate the ends of said leg, said leg being foldable medially of said neck opening and transversely of itself to provide upper waist front and back members open at the sides, a portion of said leg between said neck opening and the bar adapted to be positioned between the legs of the wearer and covering the lower front and back portions of the body, and open at the sides, the bar being reversely foldable upon itself, the free ends of said bar being extensible about the hips of the wearer for overlapping engagement, means for detachably securing the open sides of said waist members and additional means to detachably secure said free ends of said skirt portion and additional means to detachably secure the open sides of said skirt portion, said first mentioned means comprising a pair of ties on each side edge of the waist front and a pair of side edge loops on the waist back, the pairs of ties being adapted to pass across the waist front in straddling relation thereto with one tie of each pair extending out of the neck opening and the other tie of each pair extending through one of said edge loops with the ends of the pairs of ties fastened in front of said waist front.

3. A garment comprising a unitary substantially T-shaped robe with the leg of the T constituting a body portion and the bar of the T constituting a skirt portion, a neck opening intermediate the ends of said leg, said leg being foldable medially of said neck opening and transversely of itself to provide upper waist front and back members open at the sides, a portion of said leg between said neck opening and the bar adapted to be positioned between the legs of the wearer and covering the lower front and back portions of the body, and open at the sides, the bar being reversely foldable upon itself, the free ends of said bar being extensible about the hips of the wearer for overlapping engagement, means for detachably securing the open sides of said waist members and additional means to detachably secure said free ends of said skirt portions and additional means to detachably secure the overlapping ends of said bar, said last mentioned means comprising a pair of oppositely extending ties on the skirt portion for wrapping therearound and tying to the corners thereof.

HORTENSE WAHLBERG.

REFERENCES CITED

The following references are of record in the file of this patent:

UNITED STATES PATENTS

Number	Name	Date
1,993,568	Rosenberg	Mar. 5, 1935
1,351,537	Reynard	Aug. 31, 1920
1,292,703	Carter	Jan. 28, 1919
1,424,318	Nester	Aug. 1, 1922
1,475,892	Sohn	Nov. 27, 1923